UNITED STATES PATENT OFFICE.

FRED F. LATSHAW, OF ALLEGAN, MICHIGAN.

REVERSE-GEAR.

1,260,780.

Specification of Letters Patent. Patented Mar. 26, 1918.

Application filed March 10, 1917. Serial No. 154,022.

To all whom it may concern:

Be it known that I, FRED F. LATSHAW, a citizen of the United States, residing at Allegan, county of Allegan, State of Michigan, have invented certain new and useful Improvements in Reverse-Gears, of which the following is a specification.

This invention relates to reverse gears.

The objects of the invention are:

10 First, to provide means whereby the reverse gear may be actuated either manually or by power.

Second, to provide a combined manual and power gear operating mechanism in 15 which the means for controlling the power operating mechanism is located upon the reverse lever.

Third, to provide a device of the kind described which is positive in action, requires but very little steam for the operation of the same, and no steam when not in action.

Fourth, to provide a reverse lever having a very short throw in cab.

25 Fifth, to provide a reverse gear operating mechanism in which combined manual and steam power may be employed, the amount of manual power necessary being very small.

Further objects, and objects relating to 30 structural details, will definitely appear from the detailed description to follow.

I accomplish the objects of my invention by the devices and means described in the following specification. The invention is 35 clearly defined and pointed out in the claims.

A structure which is a preferred embodiment of my invention is clearly illustrated in the accompanying drawing forming a 40 part of this specification, in which:

Figure I is a side elevation of a portion of a locomotive equipped with my improved reverse gear operating mechanism, portions of the locomotive and cab being broken away to more clearly disclose my improvements.

Fig. II is an enlarged detail view showing the cylinder of my reverse gear mechanism in vertical section and a portion of the connections between the piston thereof and the link lifting mechanism in elevation.

Fig. III is an enlarged detail view showing portions of the reverse lever in elevation and showing the valve mechanism in section on a line corresponding to the line 3-3 of Fig. IV.

Fig. IV is an enlarged detail section on line 4-4 of Fig. III.

Fig. V is an enlarged detail section of the reverse lever on a line corresponding to line 5-5 of Fig. I.

Fig. VI is an enlarged detail section taken on a line corresponding to line 6-6 of Fig. V.

Fig. VII is a side elevation of the top 65 portion of my reverse lever.

Fig. VIII is an enlarged detail section taken on line 8-8 of Fig. III.

Fig. IX is an enlarged vertical section of my pressure reducing valve taken on a line 70 corresponding to line 9-9 of Fig. X.

Fig. X is an enlarged detail section taken on a line corresponding to line 10-10 of Fig. IX.

In the drawing, similar reference characters refer to similar parts throughout the several views and the sectional views are taken looking in the direction of the little arrows at the ends of the section lines.

My invention is adapted to be used in connection with any reverse gear in which the reversing of the locomotive or engine is accomplished by either manually or automatically lifting a reversing link or displacing an equivalent element.

In the drawings, 1 indicates a reverse shaft upon which is mounted the reverse shaft lever 2, the forward end 3 of which is adapted to be connected to a reverse link, which is not shown, in such a manner that when the lever 2 is oscillated about the shaft 1, the reverse link

will be moved to its extreme positions in order to reverse the direction of movement of the locomotive or engine.

A link 4 connects the upper ends of the lever 2 with the upper 90 end of the lever 5 pivoted to the frame at 6.

The reach rod 7 is pivotally connected to the bottom end of the lever 5 at one end and its opposite end is bifurcated and pivoted adjacent the lower end of the reverse lever 8 as indicated at 9 in Fig. V.

The reverse lever 8 is pivoted to the frame at 10 and is provided with a longitudinally reciprocatable detent 11 which comprises an upper and lower portion pivotally secured thereto at 105

12. The detent coacts with the toothed quadrant 15. A tension spring 16 has one end secured to the detent 11 by a pin 17 and the other end secured to the quadrant

12. The detent coacts with the toothed quadrant 15. A tension spring 16 has one end secured to the detent 11 by a pin 17 and the other end secured to the quadrant by a pin 18. This spring tends to hold the 110 detent in engagement with the teeth of the quadrant.

Adjacent the upper ends of the reverse lever 8 is an offset bracket 19 between which and the upper ends of the reverse lever is pivotally mounted a detent control handle 20. The pivot 21 for this handle is provided with an extension 22 forming a second handle by means of which the reverse lever may be operated after the detent 11 is disengaged by means of the handle 20.

10 The handle 20 is provided with oppositely extending lobes 23 and 24 which are adapted to engage the stops 25 and 26 respectively, to limit the movement of the handle in either direction. Pins 27 and 28 are secured in the lobes 23 and 24, respectively, and project through curved slots 29 and 30, respectively at the top of the reverse lever 8. The pins 27 and 28 are made long enough so that they engage the walls of the slots 31 and 32 in the bifurcations 33 and 34, respectively, of the top portion of the detent 11.

15 It will be clear from the structures just described, that the detent 11 will be lifted when the handle 20 is moved to either its forward or rearward position, thereby releasing the reverse lever. When it is desired to manually operate the reverse gear, it is merely necessary to tilt the handle forwardly or backwardly and then exert sufficient pressure upon the handle 22 to move the reverse lever 8 in the desired direction. When the desired adjustment has been made, the handle 20 is released and the reverse lever 8 is locked in its adjusted position.

20 25 The force necessary to operate certain types of reverse gear is considerable, and in order to lessen the amount of exertion necessary on the part of the engineer to perform this operation, I provide the following means: The lobe 23 of the handle 20 is provided with an extension 35 to which one end of the pitman 36 is pivotally connected as shown at 37. The opposite end of the pitman 36 is pivotally connected to the upper end of the sliding link 38 as indicated at 39. Clips 40 engage the top of the sliding link 38 and the edges thereof, as well as the edges of the detent 11, and are secured to the reverse lever 8. These clips act as guides for the sliding link 38 and the reverse lever.

25 30 A lever 41 is pivotally supported on the frame work of the locomotive as shown at 42, and has one end pivoted to the bottom end of the sliding link 38, as indicated at 43. The opposite end of the lever 41 is pivoted to the upper end of the piston rod 44, as shown at 45 in Fig. VIII of the drawing. The lower end of the piston rod 44 is provided with a piston valve 46, which controls the flow of steam from the inlet port 47 to the outlet ports 48 and 49 respectively, and to the exhaust ports 50 and 51, respectively, which are connected to a manifold 52 that discharges through the exhaust pipe 53 above

35 40 45 50 55 60 65 70 75 80 85 90 95 100 105 110 115 120 125 130 the ash pit or any other desired location.

A pipe 54 supplies steam to the pilot valve and the pipes 55 and 56, respectively, convey the steam to the opposite end of the cylinder 57. The cylinder 57 is provided with a piston 58 having a piston rod 59, which is connected by the bifurcated link 60 with the lever 5 between its supporting pivot and its lower end, as at 61. A cross head 62 is secured to the outer end of the piston 58 as by a pin 63 and reciprocates upon the slideway 64. The outer end of the slideway 64 extends between the bifurcations 65 of the lower end of the lever 5, as shown in Figs. I and II.

When the handle 20 is tilted in a forward direction, the extension 35 is carried downwardly and by means of the pitman 36, sliding links 38, lever 41 and piston rod 45, the piston valve 46 is lifted upwardly to establish communication between the inlet port 54 and the outlet pipe 55. The pipe 55 conducts steam to the right hand end of the cylinder which actuates the piston 58 in a rearward direction. The air or steam in the left hand end of the piston 57 is displaced through the pipe 55, the lower end of the pilot valve casing 46, exhaust port 51 and pipe 53.

When the steam pushes the piston 58 rearwardly the piston rod 59 and link 60 pull the bottom end of the lever 55 rearwardly and through the link 4 and the lever 2 and the reversing links are adjusted to one of their extreme positions. The handle 20 is then released, whereupon the spring 16 pulling upon the lower end of the handle of the detent 11 restores the handle 20 to its normal position and the piston valve 46 to its neutral position, thereby cutting off the steam from the pipe 54 to the pipe 55. When the handle 20 is tilted in the opposite direction, the piston valve 46 is forced downwardly, thereby allowing steam to pass from the pipe 54 through the pipe 56 to the left hand end of the piston 57. The steam displaces the piston 58 forwardly and through the piston rod 59 and link 60 moves the lower end of the lever 5 forwardly and thereby adjusts the reversing link to its other extreme position.

If it is desired to operate the reversing gear manually, it is simply necessary for the engineer to tilt the handle 20 far enough to release the detent 11 from the teeth of the quadrant but not far enough to move the piston valve 46 to a position where it would admit steam to either the pipe 55 or the pipe 56. By grasping the handle 22, the engineer can then manually operate the reverse gear.

Since it is not desirable to use the high pressure steam of a boiler for operating the piston 58, I provide a pressure reducing valve 66 which I interpose between the boiler and the pilot valve. Referring to

Figs. IX and X, it will be seen that my pressure reducing valve comprises inlet and outlet ports 67 and 68, separated by a conical valve seat 69, and a conical valve 70. The inlet port 67 is semi-annular in horizontal cross section, as shown in Fig. X and discharges through the wall of the valve seat 69. The outlet port 68 communicates with a vertical cylinder or cylindrical chamber 71 above the valve seat 69. A piston 72 reciprocates in the chamber 71 and is urged downwardly by a spring 73, the tension of which may be adjusted by a screw plug 74 in the upper end of the chamber 71. A removable cap 75 allows access to the plug 74. The piston 72 is secured to the valve 70 by means of a rod 76. The lower end of the valve 70 is cylindrical and slides in a recess 77, which is closed by a removable cap 78. In practice, the space between the two ends of the balanced piston valve 46, the pipe 54 and the portion of the chamber 71 beneath the piston 72 are always filled with steam. The pressure of this steam depends upon the tension of the spring 73. When the device is first placed in operation, the spring 73 holds the conical valve 70 in its lowermost position so that steam passes through the end of the piston 57 and is discharged through the pipe 55, the lower end of the pilot valve casing 46, exhaust port 51 and pipe 53.

rod pivotally connected intermediate the pivot and the lower end of said lever, a pilot valve controlling the admission of steam to the ends of said cylinder, means for supplying steam to said pilot valve from the boiler of a locomotive at reduced pressure, and means for controlling said pilot valve comprising a lever pivoted intermediate its ends, a link slidably mounted upon said reverse lever, one end of said lever being pivotally connected to the piston rod of said pilot valve, the other end of said lever being pivotally connected to said link, and a pitman connecting the opposite end of said sliding link with an extension of said detent releasing handle, substantially as described.

2. In a structure of the class described, the combination with a reverse link shifting means and a reverse lever, of a lever pivoted intermediate its end to the frame of a locomotive, a reach rod pivotally connected to the lower end of said lever and said reverse lever, a link pivotally connecting the upper end of said lever to said reverse link shifting means, a quadrant adjacent the lower end of said reverse lever, a detent mounted to reciprocate longitudinally of said reverse lever, the upper end of said detent being bifurcated and the arms slotted, a detent releasing handle pivotally mounted to the upper end of said reverse lever and provided

35 In the accompanying drawing various of the parts are shown mainly in conventional form as the structural details thereof form no part of this invention. I have not attempted to illustrate or describe certain modifications and structural details as I believe the disclosure made will enable those skilled in the art to which my invention relates to embody or adapt the same as may be desired.

Having thus described my invention, what I claim as new and desire to secure by Letters Patent, is:

1. In a structure of the class described, the combination with a reverse link shifting means and a reverse lever, of a lever pivoted intermediate its end to the frame of a locomotive, a reach rod pivotally connected to the lower end of said lever and said reverse lever, a link pivotally connecting the upper end of said lever to said reverse link shifting means, a quadrant adjacent the lower end of said reverse lever, a detent mounted to reciprocate longitudinally of said reverse lever, the upper end of said detent being bifurcated and the arms slotted, a detent releasing handle pivotally mounted to the upper end of said reverse lever and provided with pins upon opposite sides of said pivot point for engaging the ends of said slots, whereby said detent may be lifted by actuating said handle in opposite directions, a cylinder provided with a piston and a piston rod of said pilot valve, the other end of said lever being pivotally connected to said link, and a pitman connecting the opposite end of said sliding link with an extension of said detent releasing handle, substantially as described. 110

2. In a structure of the class described, the combination with a reverse link shifting means and a reverse lever, of a lever pivoted intermediate its end to the frame of a locomotive, a reach rod pivotally connected to the lower end of said lever and said reverse lever, a link pivotally connecting the upper end of said lever to said reverse link shifting means, a quadrant adjacent the lower end of said reverse lever, a detent mounted to reciprocate longitudinally of said reverse lever, the upper end of said detent being bifurcated and the arms slotted, a detent releasing handle pivotally mounted to the upper end of said reverse lever and provided with pins upon opposite sides of said pivot point for engaging the ends of said slots, whereby said detent may be lifted by actuating said handle in opposite directions, a cylinder provided with a piston and a piston rod of said pilot valve, the other end of said lever being pivotally connected to said link, and a pitman connecting the opposite end of said sliding link with an extension of said detent releasing handle, substantially as described. 115

3. In a structure of the class described, the combination with a reverse link shifting means and a reverse lever, of a lever pivoted intermediate its end to the frame of a locomotive, a reach rod pivotally connected to the lower end of said lever and said reverse lever, a link pivotally connecting the upper end of said lever to said reverse link shifting means, a quadrant adjacent the lower end of said reverse lever, a detent mounted to reciprocate longitudinally of said reverse lever, the upper end of said detent being bifurcated and the arms slotted, a detent releasing handle pivotally mounted to the upper end of said reverse lever and provided with pins upon opposite sides of said pivot point for engaging the ends of said slots, whereby said detent may be lifted by actuating said handle in opposite directions, a cylinder provided with a piston and a piston rod of said pilot valve, the other end of said lever being pivotally connected to said link, and a pitman connecting the opposite end of said sliding link with an extension of said detent releasing handle, substantially as described. 120

4. In a structure of the class described, the combination with a reverse link shifting means and a reverse lever, of a lever pivoted intermediate its end to the frame of a locomotive, a reach rod pivotally connected to the lower end of said lever and said reverse lever, a link pivotally connecting the upper end of said lever to said reverse link shifting means, a quadrant adjacent the lower end of said reverse lever, a detent mounted to reciprocate longitudinally of said reverse lever, the upper end of said detent being bifurcated and the arms slotted, a detent releasing handle pivotally mounted to the upper end of said reverse lever and provided with pins upon opposite sides of said pivot point for engaging the ends of said slots, whereby said detent may be lifted by actuating said handle in opposite directions, a cylinder provided with a piston and a piston rod of said pilot valve, the other end of said lever being pivotally connected to said link, and a pitman connecting the opposite end of said sliding link with an extension of said detent releasing handle, substantially as described. 125

which means whereby said defendant may be 130

- lifted by actuating said handle in opposite directions, a cylinder provided with a piston and a piston rod pivotally connected to said lever, a pilot valve controlling the admission of steam to the ends of said cylinder, means for supplying steam to said pilot valve from the boiler of a locomotive, and means for controlling said pilot valve comprising said detent releasing handle, substantially as described.
4. In a structure of the class described, the combination with a reverse link shifting means and a reverse lever, of operating connections connecting the lower end of said reverse lever to said reverse link shifting means, a quadrant for said reverse lever, a detent coacting therewith mounted to reciprocate longitudinally of said reverse lever, a detent releasing handle pivotally mounted adjacent the top of said reverse lever and provided with means to lift said detent when actuated in opposite directions, power actuated means for operating said shifting means comprising a cylinder provided with a piston having operating connections with said reverse link shifting means, and means to control the admission of steam to either end of said cylinder comprising a pilot valve, and means connected to said detent releasing handle to shift said pilot valve in opposite directions when said detent handle is actuated in opposite directions, and means for supplying steam from a locomotive boiler to said pilot valve at a reduced pressure, substantially as described.
5. In a structure of the class described, the combination with a reverse link shifting means and a reverse lever, of operating connections connecting the lower end of said reverse lever to said reverse link shifting means, a quadrant for said reverse lever, a detent coacting therewith mounted to reciprocate longitudinally of said reverse lever, a detent releasing handle pivotally mounted on said reverse lever and provided with means to lift said detent when actuated in opposite directions, power actuated means for operating said shifting means comprising a cylinder provided with a piston having operating connections with said reverse link shifting means, and means to control the admission of steam to said cylinder comprising a pilot valve, and means connected to said detent releasing handle to shift said pilot valve in opposite directions, and means for supplying steam from a locomotive boiler to said pilot valve, substantially as described.
6. In a structure of the class described, the combination with a reverse link shifting means and a reverse lever, of means for connecting said reverse lever to said reverse link shifting means to operate the latter, a detent mounted on said reverse lever, a detent lever secured to said reverse lever and provided with means for actuating said detent in the same direction when the detent handle is shifted in opposite directions, power actuated means connected to said connecting means to actuate said link shifting means, and means for controlling said power actuated means connected to said detent actuating handle, substantially as described.
7. In a structure of the class described, the combination with a reverse link shifting means and a reverse lever, of means for connecting said reverse lever to said reverse link shifting means to operate the latter, a detent on said reverse lever, a detent lever provided with means for actuating said detent, power actuated means connected to said connecting means to actuate said link shifting means, and means for controlling said power actuated means connected to said detent actuating means, substantially as described.
8. In a structure of the class described, the combination with a link shifting mechanism and a reverse lever, of power actuated means connected to operate said link shifting means, a quadrant for said reverse lever, a detent for said reverse lever mounted upon said reverse lever, and means for controlling said power actuated means connected with said detent, substantially as described.
9. In a structure of the class described, the combination with a link shifting mechanism and a reverse lever for actuating said link shifting mechanism, of a detent for said reverse lever mounted thereon, a handle pivotally mounted upon said reverse lever, the said reverse lever and pivoted handle being provided with coacting stops for limiting the movement of the handle in either direction relative to said reverse lever, and a lost motion connection between said handle and said detent at either side of the pivotal point of said handle, whereby when the handle is tilted in either direction the detent is lifted.
- In witness whereof, I have hereunto set my hand and seal in the presence of two witnesses.
